UNITED STATES PATENT OFFICE.

FRED E. KLING, OF YOUNGSTOWN, OHIO.

HOT-BLAST STOVE.

Application filed June 27, 1922. Serial No. 571,181.

To all whom it may concern:

Be it known that I, FRED E. KLING, a citizen of the United States, and resident of Youngstown, in the county of Mahoning and State of Ohio, have invented certain new and useful Improvements in Hot-Blast Stoves, of which the following is a specification.

This invention relates to hot blast stoves and more particularly to the checkerwork of said stoves, and has for one of its objects the provision of a novel checkerwork construction adapted to provide vertical checkerwork flues of increasing diameter from a point intermediate their ends to their tops.

Another object is to provide a checkerwork that will not clog as readily as checkerwork commonly in use.

A further object is to provide a checkerwork baffle above the vertical checkers adapted to catch and remove some of the dust and dirt carried in the gases used in heating the stove, and to also cause a more even distribution of the gases through the vertical checkerwork.

A still further object is to provide a hot blast stove having the novel construction, combination of parts, and design set forth in the following specification and illustrated in the accompanying drawings, in which—

Figure 1 is a vertical section through a stove constructed in accordance with this invention.

Figure 2 is a vertical section through the upper portion of a central combustion chamber stove constructed in accordance with this invention.

Figure 3 is a somewhat diagrammatic section of checkerwork constructed in accordance with my invention.

Figure 4 is a plan view of a portion of checkerwork.

The stove illustrated is as a whole a well known design, the improvement being in the checkerwork construction. The stove comprises a cylindrical side wall composed of an outer metal shell 2 and a brick lining wall 3, a dome-shaped top composed of an outer metal shell portion 4 and inner brick wall 5, and a bottom wall composed of an outer metal shell 6 and an inner wall 7. The shells 2, 4 and 6 are all secured together by riveting or otherwise to form a rigid structure, and the brick lining walls 3, 5 and 7 are all built integral.

The stove is provided with the usual com-

bustion chamber 8 and vertical checkerwork flues 9. The checkerwork 9 is supported on an arch 10 which forms a distributing chamber at the bottom of the stove, which communicates with the usual arched distributing channels 11 adapted to evenly distribute the blast through the checkers.

A hot blast outlet and gas inlet 12 is formed in the side wall of the stove and communicates with the combustion chamber 8, and a cold blast inlet 13 is formed in the side wall of the stove and communicates through the distributing chamber with the lower end of the checkerwork flues 9.

The chamber formed by the arch 10 also serves as an outlet for the burnt gases which pass through suitable passageways 14 to the flues leading to the stack (not shown), said flues being closed when the stove is in blast.

The top wall composed of the shell portion 4 and brick lining 5 is so formed that a space 15 is left between the shell 4 and wall 5, therefore, leaving room for expansion of the brick walls of the furnace when it is heated.

The vertical checkerwork flues 9 have their side walls tapered or reduced in cross section from a point 16 intermediate their ends to their tops and their upper ends are tapered to a still thinner cross section at 17 forming wedge shaped upper ends. The thinning or reducing of the side walls of the vertical checkerwork flues 9 serves to enlarge the upper ends of the flues and to, therefore, increase the length of time the stove may be operated before said flues become clogged by the dust and dirt which collects or adheres to the upper portion of the flues 9 and becomes sintered thereon.

A plurality of horizontal checkerwork flues 18 are built above the flues 9 and serve to separate the combination chamber 8 and vertical flues 9. The flues 18 are materially larger than the flues 9 and serve as baffles for the gases passing from the chamber 8 into the flues 9. The flues 18 also serve to baffle out a considerable portion of the dust and dirt carried by the gases, and to cause a more even distribution of the gases in the flues 9.

The central combustion stove shown in Figure 2 has vertical checkerwork flues 9 and horizontal checkerwork flues 18 constructed in accordance with this invention, as illustrated in Figures 1, 3 and 4, the only difference being that in the side combustion

stove of Figure 1 the horizontal checker-work flues are formed as a curved wall across the stove, since the combustion chamber is to the one side of the stove. While in 5 the central combustion chamber stove of Figure 2 the horizontal checkerwork flues 18 form a complete circle around the central combustion chamber.

The advantages of this invention will be 10 readily apparent to those skilled in the art.

By constructing the checkerwork in accordance with this invention the length of time a stove can be kept in uninterrupted operation is increased. Assuming, for instance, that with a four inch vertical flue 15 the stove has to be taken off after the flues have been decreased by the accumulation of sintered dust to 2 inches, the flue area lost by the dust is $4^2 - 2^2$ or 12 square inches.

20 Now assuming that the flue walls reduced so as to increase their area from 4 to $4\frac{1}{4}$ inches for a short length and then further decreased so as to increase the area of the flues to 6 inches, the area lost would be 25 $6^2 - 2^2 = 32$ square inches, which shows that it would require $32/12$ or $2\frac{2}{3}$ as much time to reduce the area of the flues to 2 square inches or to the minimum size at which the stove can be operated successfully.

30 It will be understood that while the flues are enlarged to 6 inches for only a short distance and decreased to $4\frac{1}{4}$ inches and then to 4 inches, that the dust accumulation also decreases and, therefore, the reduction in 35 flue area is approximately equal along the flues.

The above figures are based upon the stove without taking the horizontal flues 18 into consideration and, therefore, since these 40 flues also serve to reduce the dust accumulation on the flues 9 the length of time that the stove may be operated without becoming clogged will be still further increased.

I claim:—

45 1. In a hot blast stove, a plurality of relatively small vertical flues forming vertical checkerwork, said flues having their walls reduced in thickness from a point intermediate their ends to their top and having wedge-shaped tops, and a plurality of relatively large horizontal flues forming horizontal checkerwork above said vertical flues, said horizontal checkerwork communicating with the combustion chamber and with the distributing chamber above said vertical flues, all substantially as and for the purpose described.

50 2. In a hot blast stove, a plurality of relatively small vertical flues forming vertical checkerwork, and a plurality of relatively large horizontal flues forming horizontal checkerwork above said vertical flues, said horizontal checkerwork communicating with the combustion chamber and the distributing 55 chamber above said vertical flues, all

substantially as and for the purpose described.

3. In a hot blast stove, having a combustion chamber and a distributing chamber, a plurality of vertical flues forming vertical 70 checkerwork, said flues having their walls reduced in cross section from a point intermediate their ends to a point adjacent their upper end and having their upper ends tapered to a still thinner cross section forming 75 wedge shaped upper ends, to enlarge the diameter of said flues and materially increase the length of time said flues may be operated before they become clogged by the accumulation of dust and dirt deposited there- 80 on by the gases.

4. In a hot blast stove, having a combustion chamber and a distributing chamber, a plurality of vertical flues forming vertical 85 checkerwork, said flues having their walls reduced in cross section from a point intermediate their ends to a point adjacent their upper end and having their upper ends tapered to a still thinner cross section forming wedge shaped upper ends, and means 90 above said checkerwork for removing and catching some of the dust and dirt in the gases before they enter said checkerwork.

5. In a hot blast stove, having a combustion chamber and a distributing chamber, 95 a plurality of vertical flues forming vertical checkerwork, said flues having their walls reduced in cross section from a point intermediate their ends to a point adjacent their upper end, and having their upper ends 100 tapered to a still thinner cross section forming wedge shaped upper ends, and horizontal checkerwork above said vertical flues, said horizontal checkerwork being adapted to baffle the gases before they enter said vertical flues, thereby removing a portion of the dust and dirt carried by said gases prior to 105 their entering said vertical flues and also causing an even distribution of gases to said vertical flues.

6. In a hot blast stove, having a combustion chamber and a distributing chamber, a plurality of vertical flues forming vertical checkerwork, said flues having their walls reduced in cross section from a point intermediate their ends to a point adjacent their upper end, and having their upper ends tapered to a still thinner cross section forming wedge shaped upper ends, and horizontal 115 flues forming horizontal checkerwork 120 above said vertical flues, said horizontal flues having a greater cross sectional area than said vertical flues, communicating with the combustion chamber and with the distributing chamber of said stove and being adapted to baffle the gases before they enter 125 said vertical flues.

In testimony whereof I have hereunto set my hand.

FRED E. KLING.
